(57) **CLAIM**

The ornamental design for a glove dispenser, as shown and described.

DESCRIPTION

FIG. 1 is a front perspective view of a glove dispenser; FIG. 2 is a front elevation view of the glove dispenser; FIG. 3 is a rear elevation view of the glove dispenser; FIG. 4 is a left side elevation view of the glove dispenser, the right side elevation view being a mirror image thereof; FIG. 5 is a top plan view of the glove dispenser; FIG. 6 is a bottom plan view of the glove dispenser; and, FIG. 7 is a left side elevation view of the glove dispenser, with dispenser items shown in broken lines.

The broken lines shown in the drawings illustrate environment, specifically dispenser items, that form no part of the claimed design.

The appearance of any portion of the glove dispenser between the symbolic break lines shown in FIGS. 1 and 4-7 form no part of the claimed design.
